(57) **CLAIM**

The ornamental design for a respirator outer cover, as shown and described.

DESCRIPTION

FIG. 1 is a front perspective view of a respirator outer cover, showing my new design;

FIG. 2 is a rear perspective view thereof;

FIG. 3 is a right side view thereof, the left side being a mirror image of the right side view;

FIG. 4 is a top view thereof; and,

FIG. 5 is a bottom view thereof.

The broken lines in the drawings depict portions of the respirator outer cover that form no part of the claimed design.
